(57) **CLAIM**

The ornamental design for "casing for data processing equipment," as shown and described.

DESCRIPTION

FIG. 1 is a perspective front, top and right side view of a casing for data processing equipment in accordance with our new design;

FIG. 2 is a right side view thereof;

FIG. 3 is a left side view thereof;

FIG. 4 is a rear view thereof;

FIG. 5 is a bottom view thereof;

FIG. 6 is a perspective front, top and right side view of a second embodiment of a casing for data processing equipment in accordance with our new design;

FIG. 7 is a right side view thereof;

FIG. 8 is a left side view thereof;

FIG. 9 is a rear view thereof;

FIG. 10 is a bottom view thereof;

FIG. 11 is a perspective front, top and right side view of a third embodiment of a casing for data processing equipment in accordance with our new design;

FIG. 12 is a right side view thereof;

FIG. 13 is a left side view thereof;

FIG. 14 is a rear view thereof; and,

FIG. 15 is a bottom view thereof.

The broken line showing of various surface structures and features is included for the purpose of illustrating environmental structure only and forms no part of the claimed design.
